Primary Examiner — Robert A Delehanty(74) *Attorney, Agent, or Firm* — Gronholm Patent Services LLC**CLAIM**

The ornamental design for an toilet seat and urinal assembly, as shown and described.

DESCRIPTION

FIG. 1 is a perspective view of a toilet seat and urinal assembly according to the present design;

FIG. 2 is a left-side elevational view thereof;

FIG. 3 is a right-side elevational view thereof;

FIG. 4 is a rear elevational view thereof;

FIG. 5 is a front elevational view thereof;

FIG. 6 is a top plan view thereof; and,

FIG. 7 is a bottom plan view.

The broken lines shown in the drawings represent unclaimed portions of the toilet seat and urinal assembly and form no part of the claimed design.

1 Claim, 7 Drawing Sheets(56)
